CONTAINER

Wallace C. Mills, Rockford, Ill., assignor to J. L. Clark Manufacturing Co., Rockford, Ill., a corporation of Illinois

Application October 13, 1932. Serial No. 637,572

4 Claims. (Cl. 221—62)

The invention pertains to containers for condiments and the like and has especial reference to a container having pouring and sifter holes adapted to be covered or uncovered by a slide 5 mounted in the top wall of the container.

The object of the present invention is to make provision for a pouring spout adapted for use in conjunction with the pouring opening when the slide is in a position to cover the sifter holes and 10 thereby facilitate the removal of the contents of the can by pouring.

In the accompanying drawing, forming part hereof, Figure 1 is a perspective view of a container embodying the invention in a preferred 15 form.

Fig. 2 is a top view of the container.

Fig. 3 is a fragmentary vertical sectional view taken in the plane of line 3—3 of Fig. 2.

Fig. 4 is a transverse sectional view through 20 the upper end of the container and taken in the plane of line 4—4 of Fig. 3.

The container comprises, in the embodiment illustrated, a body 7 having an upper end or top wall comprising a top plate 8 secured to the upper 25 edge of the body in any suitable way as by means of a seam 9. The top plate 8 is apertured to provide a relatively large opening of oval shape, defined by an upstanding rib 10 having a down-turned friction flange 11. Into this opening is 30 frictionally fitted a removable cover, generally designated 12, to complete the top wall.

The cover 12 comprises a flat plate 13 with a vertical side flange 14 adapted to engage with the flange 11 of the top plate. The upper edge of 35 this flange 14 terminates in a lateral bead 14^a in the form of an inwardly opening fold, which bead forms a stop on the cover for engagement with the rib 10 on the top plate.

The cover plate 13 is provided with a series of 40 sifter holes 15 and a pouring hole 16; mounted to slide upon the plate 13 exteriorly thereof, is a slide plate 17 having a series of sifter holes 18 and a pouring hole 19. The slide is adapted to 45 occupy any one of three positions. In one of these positions (Fig. 1) both sets of sifter holes 15 and 18 and the two pouring holes 16 and 19 are out of registry and hence the slide is in what may be termed a closed position. In another position (Figs. 2 and 3), the pouring holes 16 and 50 19 are in registry and in this position the two sets of sifter holes are out of registry. In the first position, the slide is in its extreme left hand position as shown in Fig. 1, and in the other instance the slide is in its extreme right hand position 55 as shown in Figs. 2 and 3. In a third or interme-

diate position, the pouring holes 16 and 19 are out of registry and the sifter holes 15 and 18 are in registry.

The slide plate 17 is retained in position upon the cover plate 13 by means of a pair of laterally 60 extending flanges or tongues 20 on opposite sides of the slide engaging in channel shaped guides 21 formed at the upper edge of the flange 14 of the cover at opposite sides thereof. The guide flanges 20 are formed at the upper edge of an upstanding flange 22 on the slide plate 17; and the channel shaped guides 21 are formed by raising the upper part of the fold which forms the head 14^a on the cover plate 13. 65

To facilitate the pouring operation when the slide is in the position shown in Figs. 2 and 3, the spout 23 is formed at one end of the slide adjacent the opening 19 therein. Preferably, this spout is formed integral with the slide, being in the present instance in the form of a rounded lip 70 projecting upwardly and outwardly from the flange 14 at the end adjacent the hole 19. It will be seen that by mounting the spout upon the slide, its proper position with respect to the pouring holes 16 and 19 is assured. At the same time, 75 the spout constitutes a practically negligible addition to the cost of construction, and it serves the added function of a finger piece by means of which the slide may be conveniently manipulated. 80

I claim as my invention:

1. A container of the character set forth having a body with an end wall comprising a top plate with a series of sifter openings therein and a pouring opening, a slide mounted on the top plate exteriorly thereof and also having sifter and pouring openings with said openings arranged so that in one position of the slide the pouring openings are adapted to register and in another position of the slide the sifter openings are adapted to register, and a spout mounted on the slide adjacent the pouring opening therein. 85

2. A container of the character set forth having a plurality of sifter openings and a pouring opening in one end wall, a slide mounted for movement on said end wall exteriorly thereof and also having a plurality of sifter openings and a pouring opening selectively movable in the operation of the slide into and out of registry with the sifter and pouring openings in the end wall, and a pouring spout formed integral with one end of the slide, the pouring opening in the slide being located adjacent said spout. 90

3. A container of the character set forth having a body with an end wall comprising a top plate with an elongated aperture therein, a clo- 100

sure plate fitted into said aperture and having a series of sifter openings therein and a pouring opening, said closure plate having an upstanding peripheral flange with laterally opening guide channels formed in opposite sides at the upper edge of the flange, a slide plate also having an upstanding flange with laterally extending tongues at the upper edge thereof entered in said channels, said slide plate having sifter openings adapted in one position of the slide to register with the sifter openings in the top plate and a pouring opening adapted in another position of the slide to register with the pouring opening in the top plate, and a pouring spout formed integral with said upstanding flange on the slide plate adjacent the pouring opening.

4. A container of the character set forth having a body with an end wall comprising a top plate with an elongated aperture therein, a closure plate fitted into said aperture and having an upstanding peripheral flange with a laterally extending bead at its upper edge in the form of an

inwardly opening fold, said closure plate having a pouring opening at one end and a plurality of sifter openings, a slide plate mounted on said closure plate exteriorly thereof and also having an upstanding peripheral flange with laterally extending tongues at opposite sides of the slide plate, said flange on the closure plate having guide channels formed in the fold of said laterally extending bead and adapted to receive said tongues, said slide plate further having sifter openings adapted in one position of the slide to register with the sifter openings in the top plate and a pouring opening at one end of the slide plate adapted in another position thereof to register with the pouring opening in the top plate, and a pouring spout adjacent said pouring opening in the slide, said spout being in the form of an extension of the peripheral flange on the slide plate at the end adjacent the pouring opening therein.
